ELECTRIC PULSE COUNTER

Werner Liebknecht, Bonn, Germany, assignor to Elmeco
A. G., Zurich, Switzerland, a Swiss company

Application May 10, 1955, Serial No. 507,424

Claims priority, application Germany May 11, 1954

1 Claim. (Cl. 235—92)

The counting of electrical pulses has become more and more important in technology; it is used as call counter and time-and-range counter in telephone systems, in all types of calculating machine, in the radiation measurements technique, in mass production and packing machines and not least in office machines, sorting and statistical equipments, etc.

Hitherto two fundamentally different types of pulse counter have been available for such problems.

For pulse sequences of up to about 50 p. p. s. (pulses per second) different varieties of the old call counters have been used, the counter continuing to be controlled mechanically by the energization and de-energization of one or several electromagnets.

When the pulse sequences reach 500 p. p. s. and more, the undisputed field of activity of the electronic counters begins. It is true that electronic counters also work perfectly down to as low a pulse sequence as desired, but at this level they cannot compete with electro mechanical counters on account of their high price and their technical requirements. For the operating range of about 10—500 p. p. s. there has so far been no counter which operates perfectly and is suitable, as regards scope and price, to meet the great demand for this range.

The known electromechanical counters with pawl control of any description were unsuited for this purpose. The drive systems were too sluggish and thus could not be used for higher pulse sequences. A particular drawback was also the fact that several elements were required for the drive, namely, armatures, thrust pawls, lock pawls and various springs. These parts produced a natural resonance at elevated pulse sequences and rendered the working of the counter unstable.

Other fundamental drawbacks were the high wear and tear and especially the great noise connected therewith which was caused by the large number of driving elements and became almost intolerable as the pulse frequency increased. All these defects are eliminated according to the present invention by the fact that a system working without flexible parts is used for the drive.

The fundamental operation diagram of a typical embodiment of the invention is illustrated in Figs. 1 and 2.

The cipher wheels *a* to *f* with the intermediate wheels *Z* form a normal 6-position counter. A magnet wheel *P* is arranged on this decade-type counter. The magnet wheel *P* is designed in ten sections according to Fig. 2 and is rigidly connected to the cipher wheel *a*. In Fig. 1 the magnet wheel *P* is drawn as an independent wheel for the purpose of illustrating the embodiment. In order to save space, the magnet wheel could, however, also carry the figure rim of the cipher wheel *a*. The cipher wheel *a* would then at the same time have the magnet wheel inside it and the width for the magnet wheel would therefore be saved. The magnet wheel *P* can of course also be connected to the cipher wheel *a* via any type of intermediate gear, insofar as this appears desirable in special cases. In Fig. 2 *E* is a winding *Sp* with a magnet core which has pole shoes tapered on one side. The arresting device

R is formed by a permanent magnet with tapering pole shoe, but can also be designed as an electromagnet. If the winding *Sp* of the magnet *E* is excited by a current, the magnet wheel *P* will advance half a step in clockwise direction and the poles 1 and 2 will now be immediately in front of the core legs of the magnet *E*. The pole 3 is moved away from the arresting magnet *R*. The latter reaches the pole 4 of the magnet wheel with the tapered end of its pole shoe.

When the pulse is over and the flow of current through the winding *Sp* ceases, the arresting magnet *R* pulls the pole 4 of the magnet wheel *P* in front of its core and with this second half-step one whole step of the cipher wheel *a* has been completed. This cycle is repeated in the same sequence at every subsequent pulse. If the tapered pole shoes of the magnet core *E* and the arresting magnet *R* in Fig. 2 are not pointed to the right but to the left, the direction of rotation of the magnet wheel will be inverse.

Thus two magnets *E* and *R* are located at the magnet wheel *P*. At least one of the magnets *E* and *R* must be excited electromagnetically, this being the magnet *E* in the construction shown in Figure 2. The magnets *E* and *R* are so arranged in relation to the poles of the magnet wheel *P* that only one of these poles can be located directly opposite one of the magnets, while the pole shoe of the other magnet will be somewhat shifted in relation to other poles of the magnet wheel *P*. For example, in Figure 2, the pole 3 of the magnet wheel *P* is located directly opposite the magnet *R*, while the poles 1 and 2 of the magnet wheel *P* are located opposite the extensions of the pole shoe of the magnet *E* which taper in the direction opposite to the direction of rotation of the magnet wheel *P*. Preferably, the arrangement is such that the main portions of the pole shoes of the magnet *E* will be located precisely between two poles of the magnet wheel *P*. Thus, by way of example shown in Figure 2, the left upper pole shoe of the magnet *E* is located precisely between poles 0 and 1 of the magnet wheel *P*, as indicated by a broken line in Figure 2.

The operation of the device may be summarized as follows:

When the magnet *E* is excited by the electrical impulses in the winding *Sp*, a magnetic field will be formed between the pole shoes of the magnet *E*, which is so powerful that the magnet wheel *P* will be turned in the direction of the arrow shown in Figure 2, until the poles 1 and 2 of the magnet wheel *P* will be located directly opposite the main portions of the pole shoes of the magnet *E*. Consequently, if the magnet wheel has ten poles it will be turned to the extent of the angle $2\pi/20$ or $\pi/10$. During this rotation the force of attraction between the magnet *R* and the pole 3 is overcome, since the electro-magnet *E* when excited by the current, is stronger than the magnet *R*. Then the pole 4 of the magnet wheel *P* will be located opposite the tapered portion of the pole shoe of the magnet *R*. This position will be maintained so long as the winding *Sp* is supplied with an electrical impulse. However, as soon as this impulse is terminated, the force of attraction of the magnet *R* will prevail, so that the pole 4 of the magnet wheel *P* will be attracted and will move to a position directly opposite the main portion of the pole shoe of the magnet *R*. Then the magnet wheel *P* will assume the same position as that shown in Figure 2, except that the poles of the magnet wheel *P* have been shifted or turned to the extent of one pole. Thus the magnet wheel *P* has now carried out a rotation to the extent of the angle $2\pi/10$ or $\pi/5$. Obviously, this procedure will be continuously repeated.

In the construction shown in Figure 2 the magnet *R* is shown as a permanent magnet. However, the magnet *R* can be also constructed as an electro-magnet which is

supplied with electrical current only when the electro-magnet E is not excited. Then the counting is carried out by a so-called double current.

This arrangement in comparison to prior art constructions has the important advantage that no mechanical pawls are required. Pawl-operated devices wear out quickly and have a substantial magnetic inertia which substantially diminishes the speed of counting.

The tapered pole shoes can also be arranged on the poles of the magnet wheel, in which case no such pole shoes are required on the magnet core E and the arresting magnet R. If, according to Fig. 1, the magnet wheel is not arranged next to the unit cipher roll, thus enlarging the width of the counter, but if the drive is placed beneath the cipher rolls, the following suitable embodiment results:

The magnet wheel is designed with a small number of poles and thus has a small diameter, i. e. small moment of inertia; it has an elongated form similar to a motor armature. A sort of "magnet wheel motor" is thus obtained for the drive of the counter.

The size of the magnet wheel or the "magnet wheel motor" beneath the cipher rolls and the dimensioning of the driving and arresting magnets can now be easily adapted to the power required to drive the counter. The width of the space taken up by the counter is not affected.

The small diameter of the magnet wheel results in a small moment of inertia and is particularly advantageous for short pulse times i. e. high counting frequencies.

With this form of drive the driving force of the "magnet wheel motor" must be transmitted to the cipher rolls via intermediate gears or silent-running transmission belts (gear-driven V-belts or similar transmission members). This additional power consumption, however, is insig-

nificant in comparison with the advantages mentioned. In particular, transmission by a gear-driven, small V-belt has proved most suitable.

It is obvious that a counter drive of this type is largely free from inertia and thus works better than the electro-mechanical counters known hitherto even at much higher impulse frequencies. It is evident that the drive of a counter driven by a magnet wheel functions almost without wear. The silent operation of the counter is also found to be particularly pleasant.

Having now particularly ascertained and described the nature of my said invention and in what manner the same is to be performed, I declare that what I claim is:

An electric pulse counter, comprising a rotary wheel 15 inducing a magnetic field and having a plurality of uniformly spaced poles, two magnets having pole shoes, each of said pole shoes having a main portion and a tapered portion extending in a direction opposite to the direction of rotation of said wheel, said pole shoes being so located 20 adjacent to different poles of the wheel that when the main portion of the pole shoe of one magnet is located directly opposite one pole of the wheel solely the tapered portion of the pole shoe of the other magnet is located directly opposite another pole of the wheel, and an exciter winding operatively connected with at least one of 25 said magnets.
